SHOULDER HOOK CRADLE FOR TELEPHONE
HANDSETS

Herman H. Renneker, San Diego, Calif.

Application June 9, 1945, Serial No. 598,573

1 Claim. (Cl. 179—157)

1 My invention relates to a shoulder hook cradle for a telephone hand set and the objects of my invention are:

First, to provide a device for holding a telephone hand set upon the shoulder of the telephone user so that the proper portions thereof are held in correct operative positions relative to the ear and mouth of the user without manual support;

Second, to provide such a device with means rendering the device easily adjustable to the individual needs of a particular user, this adjustment means allowing the adjustment of the hand set on the cradle so that the hand set will naturally assume a position allowing the normal use thereof, with the head of the user held comfortably erect;

Third, to provide such a device in an aesthetically designed form, extremely light in weight, not bulky or cumbersome, and comfortable to use;

Fourth, to provide such a device which may be easily attached to a hand set and used or not used as desired, the attached device entailing no inconvenience in using the hand set without employing the shoulder hook.

Fifth, to provide such a device in a form which is inexpensive and practicable to manufacture, convenient and simple to use, and sturdy and enduring in service.

With these and other objects in view as will appear hereinafter, my invention consists of certain novel features of construction, combination and arrangement of parts and portions as will be hereinafter described in detail and particularly set forth in the appended claim, reference being had to the accompanying drawings and to the characters of reference thereon which form a part of this application in which:

Figure 1 is a top plan view of my invention; Fig. 2 is a side elevational view of my invention; Fig. 3 is a fragmentary cross sectional view taken on a line 3—3 in Fig. 1 to show the means for making the device adjustable and generally to facilitate the illustration.

Similar characters of reference refer to similar or identical parts and portions throughout the views of the drawings.

The body portion 1, hook portion 2, pad 3, cradle 4, and cradle securing screw 5 constitute the principal parts and portions of my invention.

My invention is designed for combination with a standard hand set telephone and adapted for adjustable securement to the tubular spacer member of the set between the mouthpiece and

2 the earpiece which spacer member is usually of reasonably constant cross section over a considerable length thereof.

The body portion 1 is adapted to be placed on top of the shoulder of the telephone user and may be generally rectangular in shape with a longitudinally disposed trough 1a on the upper surface of the body portion. On the underside of the body portion 1 is provided a longitudinal channel 1b extending throughout the major portion of the body portion and communicating with the trough 1a through a slot 1c of a length nearly equal to the channel 1b.

One end of the body portion tapers into an integral curved depending hook portion 2 and on the inside of this hook portion a pad 3 of sponge rubber, felt or other material is provided to improve the gripping action of the hook on the clothing of the user of the telephone.

20 The cradle 4 is of curved U-shape with a part thereof shaped to conform with and fit into the trough 1a on the upper surface of the body portion 1. The inner concave surface of the cradle is shaped to conform with the tubular spacer member between the mouthpiece and the earpiece of a hand set which is placed therein. The hand set is secured to the cradle by the strap yoke 4a which is removably attached to the yoke by means of screws 4b and 4c. This yoke 4a holds 25 said tubular member rigidly within the cradle.

The set screw 5 is threaded into the cradle 4 through the slot 1c in the said body portion and the head of the screw 5 contacts the body portion within the channel 1a, thus allowing the longitudinal adjustment of the cradle 4 relative to the body portion 1 and firmly attaching the cradle in a predetermined position adapted to the particular needs of the user, the cradle being disposed at an angle relative to the body portion so that the hand set is inclined towards the head 30 of the user.

In using my invention, the hand set with the device attached thereto is placed so that the undersurface of the body portion 1 rests on top of the shoulder, near the neck, of the user with the hook portion 2 depending behind the shoulder. The pad 3 helps to prevent the device from slipping and mouthpiece and earpiece of the hand set will be held in proper position to allow normal use of the telephone without manual support, the hands of the user being left free for other work.

It will be seen that a shoulder-supported cradle structure embodying the present invention can be used easily and conveniently for supporting a standard telephone hand set adjacent either the

left or right side of the user's head. In order to adapt the structure for use at either the right or left side of the user's head, the screw 5 may be removed or loosened and the cradle 4 reversed or turned through 180° with respect to the body portion 1. In either of its selected positions, the cradle structure is in a plane substantially transverse to the body portion, and a line bisecting the angle between the legs of the U of the seat in the cradle portion is at such an inclination to the vertical that the hand set positioned in the seat is inclined upwardly and inwardly from the user's shoulder toward the user's head with the ends of the hand set being disposed respectively adjacent the user's mouth and ear.

Though I have shown and described a particular construction, combination and arrangement of parts and portions, I do not wish to be limited to this particular construction, combination and arrangement but desire to include in the scope of my invention the construction, combination and arrangement substantially as set forth in the appended claim.

Having thus described my invention, what I claim as new and desire to secure by Letters Patent is:

A shoulder-supported cradle structure for standard telephone hand sets, comprising a one-piece shoulder-engaging rest member having a substantially flat cradle supporting portion, the underside of which is adapted to rest upon and extend crosswise with respect to the crest of the shoulder of a user, said flat portion terminating at one end in an integral, downwardly curved hook portion, adapted to embrace an area of a user's shoulder adjacent the crest, a cradle member mounted on the upper face of said flat

portion for receiving a telephone hand set, said cradle member having a generally U-shaped seat in a plane substantially transverse to said flat portion so that a standard hand set positioned in said seat will also extend generally crosswise with respect to the user's shoulder, a line bisecting the angle between the legs of the U of said seat being at an inclination to the vertical and to the horizontal when said structure is in use, whereby the seat holds the hand set inclined upwardly and inwardly from the shoulder toward the head of the user with the ends of the hand set disposed respectively adjacent the user's mouth and ear, and means for adjustably mounting said cradle member on said flat portion comprising a longitudinally extending guide trough in the upper face of said flat portion, a projecting shoulder on said cradle member adapted to slidably engage said trough, a longitudinally extending slot in the base of said trough and an adjustable stud adapted to be inserted into said cradle through said slot for retaining said cradle in adjusted position with respect to said flat portion.
